DISPENSING MACHINE

Harvey P. Curlee, Raleigh, N. C., assignor to
 Curlee Machinery Company, Inc., a corporation
 of North Carolina

Application June 13, 1950, Serial No. 167,820

10 Claims. (CL. 221—81)

1

This invention relates to a dispensing machine. While the machine is capable of dispensing many different kinds of articles, it is particularly adapted to the vending of packages of crackers and the like.

The objects of the invention are to construct a dispensing cabinet of large capacity and in which the goods are substantially in full view; to produce an article holding magazine in which the goods are individually supported rather than being stacked on top of each other; to produce a novel coin controlled mechanism for dispensing the goods; to produce a machine in which the article discharging mechanism is separately housed, and removable from the article carrying reels, trays or racks; and to produce a dispensing machine of pleasing appearance, and including operating mechanism of simple and durable construction.

Generally these objects are obtained by mounting a plurality of independently supported circular reels or trays, one over the other, and horizontally rotatable about their vertical axis. The trays are surrounded exteriorly by a circular housing which may be entirely, or a portion thereof, transparent so that a good view of the trays is obtained. Coin controlled mechanism is provided for unlocking the operating mechanism for a plurality of trays, indexing to give an incremental rotation to a single selected tray and ejecting goods therefrom, while at the same time locking the remaining trays against movement.

The means by which the various objects of the invention are obtained are described more fully in connection with the accompanying drawings, in which:

Figure 1 is a front elevational view of the dispensing machine, partly broken away;

Figure 2 is a side elevational view of Figure 1, the side cover panel being removed;

Figure 3 is a top plan view of the machine with the top cover removed;

Figure 4 is a cross-sectional view on the line 4—4, Figure 1;

Figure 5 is an enlarged view taken on the line 5—5, Figure 2;

Figure 6 is a view similar to Figure 5 with the parts moved into another operating position;

Figure 7 is an enlarged fragmentary view similar to Figure 5, but with the parts moved into another operating position;

Figure 8 is an enlarged fragmentary view taken on the line 8—8, Figure 3;

Figure 9 is an enlarged fragmentary view of the operating mechanism in side view;

2

Figure 10 is a fragmentary view of the reverse side of Figure 9;

Figure 11 is a cross-sectional view on the line 11—11, Figure 9;

Figure 12 is a cross-sectional view on the line 12—12, Figure 10;

Figure 13 is an enlarged detailed view of part of the interlocking mechanism;

Figure 14 is a cross-sectional view on the line 14—14, Figure 13; and

Figure 15 is an exploded view of the mechanism shown in Figures 13 and 14.

In Figures 1 to 4, the dispensing machinery is contained in a cylindrical housing 2, at least a portion of which is fashioned of transparent material 4 presenting a clear unbroken view of the interior of the housing. Adjacent the transparent section 4, a sector of the cylindrical wall is omitted, as it is covered by a removably rectangular housing 6. This latter housing contains the operating mechanism for the dispenser, and forms in effect a side for the dispenser. Housing 2 is further enclosed by a bottom plate 8 and a top plate 10.

Within housing 2, and resting on bottom plate 8, is a spider 12 to which are attached four posts 14 extending vertically to, and secured to a top spider 16. Spiders 12 and 16 further joined through their centers by a rod 18. Each post 14 has a series of outwardly facing vertically spaced notches 20, Figure 8, the notches of adjacent posts lying in the same horizontal plane.

A series of annular reels or trays 22 are mounted in notches 20, said trays thus being vertically separated from each other, and the notches 22 lying in the horizontal plane of each tray forming bearing surfaces on which the respective tray can be circularly rotated. The upper surface of each tray is subdivided into a plurality of compartments by upstanding plates 24, twenty in the trays illustrated, the space between each two adjacent plates being adapted to receive an article to be dispensed or vended by the machine. Each plate 24 is tapered to be narrowed toward the center of the tray in order that the spacing between the plates is not appreciably diminished on the shortened circumference of the inner edge of the tray. The outer ends of plates 24 are spaced inwardly from the outer circumferential edge of tray 22, and this circumferential edge has a series of notches 25, each in radial alignment with a plate 24. Furthermore, the circumferential edge of each tray 22 has one arcuate recessed edge portion 26 extending between two notches 25.

mechanism 60 contains a bell crank 154, one arm 156 of which is attached to the free end of lever 146 by a rod 158, this arm being urged downwardly by spring 160. The other arm 162 extends downwardly and has its lower end joined by a right angle connection 164, Figure 11, to an arcuate push plate 166 swingable in an arcuate slot 168 formed in the supporting cover plates 170 and 172 of mechanism 60. Arm 162 is guided by bracket 174 secured to plate 170.

A bar 176, slidably held to plate 170 by brackets 178, has its upper end joined to the free end of lever 150 by rod 158. Bar 176 is urged downwardly by spring 182. A locking notch 184 is cut in one edge of bar 176. Said rod also carries an arm 186 secured to the rod through an opening in plate 170, said arm terminating in a downturned coin stop 188.

A locking bell crank 190 is pivotally secured to plate 170 adjacent bar 176, the upper arm 192 of which extends slightly inclined upwardly from the horizontal, and has at its free end a pin 194 which projects through slot 196 in plate 170. Lower arm 198 forms an obtuse angle with arm 192, and hangs inclined to the vertical and normally in locking engagement with notch 184 in bar 176.

Plate 172 is actually formed in two parts. Upper part 172a extends from the chute 58, Figure 2, to the slot 168 and forms one wall of the coin chute. The lower edge of plate 172a is curved to conform with slot 168, and one lower corner is cut away to clear slot 196. Lower portion 172b has an upper edge curved to slot 168 and then is continued into a projection 173 which is inclined on one side to form a guide for pin 194, and has another side flush with end 188 of arm 186. Portion 172b forms a cover plate for two chutes, namely the coin return chute 62a and the coin counting chute 64a.

A coin release mechanism is composed of a plate 200 extending through a slot in plate 170 into the space beneath slot 168. Plate 200 is attached to one arm of a crank 202 which is mounted on plate 170. The other arm of crank 202 is connected to horizontal rod 204, which is joined to vertical rod 206. A second crank 208 connects rod 206 to a push rod 210, having a knob 212 outwardly of panel 40. Push rod 210 is urged outwardly by spring 214. Rod 206 extends upwardly into connection with the coin release portion of the coin selector 56, the details of which are not a part of this invention.

The operation of this dispensing machine is as follows. To load the machine, housing 6 is swung open on hinges 50 to expose trays 22. Each tray has the articles to be vended placed in the compartments between plates 24, the trays being rotated by hand to make the various compartments accessible. However, the compartment twice removed to the left of the compartment on the edge of which curved notch 26 appears, is left vacant. Each tray is then rotated until the notches 26 are all aligned at the right side of the opening, note Figure 5, and housing 6 closed.

To vend an article, a coin is deposited in chute 54, said coin passing into coin selector 56, and if rejected passes directly down chute 57 into coin return chute 62. If accepted, the coin passes to mechanism 60 where it comes to rest on top of plate 200 and in front of push plate 166, Figures 9 and 10.

A knob 86, when pulled outward and then pushed inward, will discharge an article from the

tray with which the knob is horizontally aligned. Initial outward movement of a knob, Figures 5 and 6, will move rods 70 and 72 and cam 112. First, arm 98 is swung away from tray 22 as cam follower 102 leaves cam 96. Almost simultaneously, cam 112 engages between segments 134 and lifts all upper segments, this movement being transmitted through lever 146 and rod 158 to crank 154, which actuates pusher 166 to push the coin to the right in Figure 10, said coin striking pin 194 and raising it. Crank 190, Figure 9, is thus moved counterclockwise, and arm 198 is disengaged from notch 184, bar 176 being unlocked. The coin comes to rest against coin stop 188 of arm 186.

Cam 112 continues to move into engagement with notch 142 in bar 140, and lifts the bar, the motion being transmitted by lever 150 and rod 180 to lift bar 176. Arm 186 is raised and frees the coin which falls through chute 64a and counter 64 into box 66. It is noted that bar 176 cannot be lifted, and thus bar 140 cannot be moved until a coin has first been received at slot 168 to actuate crank 190. Outward movement of rod 84, and bars 70 and 72, is halted until this is done. Likewise, no other similar mechanism on the adjacent shelves can be operated as the further movement of segments 134 is stopped by arm 162 having reached its limit of movement.

Further movement of bars 70 and 72 causes arm 98 to swing to the position of Figure 6. Meanwhile, index finger 110 rides along the edge of tray 22 to engage the next notch 25. Ratchet 116 prevents a reverse movement until the end of the outward stroke.

Bar 84 is then pushed inwardly, the initial movement starting the incremental rotation of tray 22 by index finger 110. Cam follower 102 then reaches cam notch 96 and is forced into 40 notch 96 to give a positive drive to arm 98 by being pushed by crossbar 76. In completion of its movement, bumper 186 has entered into a compartment space on tray 22 and pushed an article therefrom into chute 28. Disc 108 bears 45 against either of the adjacent plates 24 and rotates tray 22 into correct alignment if such be necessary, and also holds tray 22 against further counterclockwise rotation.

At the same time cam 112 has withdrawn first 50 from beneath bar 140, this bar dropping and permitting bar 176 to fall and be locked by arm 198. Knob 86 cannot, therefore, be pulled out to reactivate the mechanism to discharge another article before another coin is inserted in the machine. Secondly, cam 112 withdraws from 55 beneath segments 134, thus permitting crank arm 156 to drop, and resetting curved push bar 166. With the knob 86 pushed all the way in, the mechanism is set for another operation cycle.

This cycle is repeated until the rotation of the tray brings notch 26 to the position of arm 90, Figure 7. At this point, tray 22 is empty, and arm 98 swings, as its end 94 is displaced, into locking engagement with notch 88, thus preventing movement of the article releasing mechanism. Of course, it should be obvious that any particular tray is empty by viewing the tray through the transparent portion of housing 2. However, lock bar 90 prevents a coin from being collected on an empty tray.

As described before, an acceptable coin deposited in chute 54 comes to rest on plate 200, Figures 9 to 12. To obtain the direct return of the coin in the event that the machine is empty, or 75 for any other reason, knob 212 is pushed inward-

ly. This swings crank 208 which lowers rod 206, and in turn lowers rod 204, to actuate crank 202, and plate 200 is withdrawn from between plates 170 and 172b, thus permitting the coin to drop into chute 62a and be returned through chute 62. Rod 206 also opens coin selector 56 so that any coin or other object which may be caught there will be removed through chutes 57 and 62.

Articles are removed from the machine by lifting door 32 and taking the article from pan 30. As cover 34 has been moved to close off the bottom of chute 28, no foreign objects can be pushed into the interior of the machine.

Having now described the means by which the objects of the invention are obtained, I claim:

1. A dispensing machine comprising a plurality of annular trays, means for supporting said trays in vertically aligned spaced relation, each of said trays being independently horizontally rotatable, a chute mounted in the center space of said annular trays vertically coextensive therewith and having an opening common to all of said trays, and means for discharging articles from said trays into said chute.

2. A dispensing machine as in claim 1, said supporting means comprising a plurality of posts, notches in each post horizontally aligned with similar notches in adjacent posts, and said trays being slidably mounted in the respective horizontally aligned notches.

3. A dispensing machine as in claim 2, a wall member secured to said posts between each vertically spaced pair of notches.

4. A dispensing machine as in claim 3, said discharging means comprising an arm swingable over a tray, a pull bar, means for locking said bar against movement, means for unlocking said bar, and cam means on said bar for swinging said arm from said tray upon movement of an unlocked bar, and upon reverse movement of said bar for swinging said bar over said tray to push an article therefrom.

5. A dispensing machine comprising a plurality of annular trays, a housing, means mounting said trays in said housing in vertically aligned spaced relation, each tray being independently rotatable about its center axis, a chute mounted in the center space of said trays and vertically coextensive therewith, a second housing, a plurality of article discharging mechanisms in said second housing each of which corresponds to one of said trays for pushing articles from said trays into said chute, respectively, and means for removably securing said second housing to said housing for said trays with each article discharging mechanism operatively mounted adjacent its respective tray.

6. A dispensing machine as in claim 5, said second housing further including a coin actuated locking mechanism, and means interconnecting said locking mechanism with each of said article discharging mechanisms.

7. In a dispensing machine having an annular tray mounted for horizontal rotation about its center, radially extending partitions on said tray adapted to separate goods to be dispensed, means for ejecting articles from said tray, and means for indexing said tray, said ejecting means comprising an ejecting bar normally extending from the outer circumference of said tray into the space between two partitions, a pull-push rod, cam means actuatable by pulling said rod for engaging said bar to withdraw said bar from the space between the partitions, means connecting said indexing means to said rod for indexing said tray upon pushing of said rod, and said cam means returning said ejecting bar to starting position between a new pair of partitions whereby an article seated between said new pair of partitions is ejected toward the center of said annular tray.

10 8. An ejecting mechanism for a dispensing machine comprising an annular tray adapted to carry articles to be dispensed, a shelf adjacent said tray, a pull-push bar slidably mounted on said shelf, an arm pivotally secured to said shelf and swingable over said shelf and said tray, and a cam on said bar engageable with said arm for effecting the swinging of said arm when said bar is moved.

15 9. An ejecting mechanism as in claim 8, said cam comprising a slot in said bar having a cam surfaced edge, and a cam follower secured to said arm and movable in said slot.

20 10. An ejecting mechanism as in claim 9, said arm further comprising an elbowed member, and said cam follower being secured to said arm at said elbow.
